UNITED STATES PATENT OFFICE

AUGUST BESSLER, OF ESSEN, GERMANY, ASSIGNOR TO FRIED. KRUPP AKTIENGESELLSCHAFT, OF ESSEN-ON-THE-RUHR, GERMANY

DYNAMIC BRAKING DEVICE FOR IDLY-RUNNING MOTORS

Application filed March 31, 1924, Serial No. 703,265, and in Germany March 31, 1923.

The invention relates to operating mechanisms for cash registers, calculating machines and the like of the kind in which at the end of an operation of the machine the coupling 5 between the driving motor and the operating shaft of the machine is released, the operating shaft is locked and the circuit supplying the motor is interrupted. A simple interruption of the circuit suffers from the drawback that 10 the motor produces a disturbing noise in slowing down without load. If, as it has been proposed, the main is connected to the motor inversely and the counter-current interrupted at the beginning of the reverse rotation of the 15 motor, this latter, it is true, will quickly come to rest, but other disadvantages will arise in this case, in particular high mechanical and electrical stresses. In order to obviate them, a switch method is made use of according to 20 the invention, which is known with motors permanently working in loaded state and in which method the armature of the motor, after being disconnected from the main, is connected to its exciting winding in inverse 25 switching direction. With this end in view the invention consists of the arrangement, construction and combination of parts to be hereinafter described and particularly pointed out in the appended claims. In order to 30 allow of the invention to be more readily understood, an embodiment of the same will now be described in detail, by way of example. In the drawing

Fig. 1 is an elevation of the mechanism in 25 position of rest,

Fig. 2 is a corresponding top view,

Fig. 3 is the section on line 3—3 of Fig. 2, seen from the left,

Fig. 4 is the section on line 4—4 of Fig. 2, 40 seen from the right;

Figs. 5 and 6 are elevations illustrating the mechanism in different working positions;

Fig. 7 shows a throw-over switch and its 45 wire connections in position of rest, and

Fig. 8 shows it in working position.

A denotes the main operating shaft of the machine which has mounted on it for free rotation a worm wheel a^1 in mesh with a worm, 50 not shown, mounted on the motor shaft. Beside the worm wheel a^1 there is arranged on

the shaft A a disk a^2 , Figs. 2 and 3, which forms part of a clutch the other parts of which are lodged within the worm wheel a^1 . This clutch is known per se and needs no description in detail. It acts in a manner such 55 as to cause the worm wheel a^1 which is rotated by the motor in the direction of the arrow, Fig. 1, to automatically couple itself to the shaft A as long as the disk a^2 is not hindered from taking part in the rotation of said worm wheel. When the rotation of the disk a^2 is stopped, the worm wheel a^1 will be uncoupled from the shaft A. The disk a^2 carries a lateral lug a^3 , see particularly Fig. 60 3, adapted to co-operate with a laterally bent lug b^1 of a locking lever B. This lever B is pivoted on the axle b^2 mounted on the frame of the machine, and is acted upon by a spring b^3 and a thrust bar b^4 . This latter is connected to it by means of a pin b^6 engaging a 65 slot b^5 of the bar b^4 .

The free end of the lever B shows a surface b^7 which in the position of rest of the mechanism, Fig. 1, abuts against a lateral lug c^1 of a locking disk C rigidly fixed on the shaft A. 75 Besides this disk C there is arranged on the shaft A a switch disk C^2 which is adapted to rotate within certain limits and tends to turn a spring c^3 , wound on the shaft A, in the direction of the arrow, Fig. 1. The rotating motion 80 of the disk C^2 with respect to the disk C, and therewith to the shaft A, is limited by a pin c^4 fixed on the disk C and engaging a slot c^5 concentric with the shaft A, of the switch disk C^2 . When the mechanism is in position 85 of rest the lug b^1 of the locking lever B locks the switch disk C^2 by abutting against a lateral lug c^6 fixed on said disk, the pin c^4 lying in this position in the lower end of the slot c^5 , Fig. 1. Furthermore, in this position a 90 notch c^7 provided on the periphery of the disk C and a notch c^8 provided on the periphery of the disk C^2 are situated beside one another. A roll d^1 abuts against the periphery of the disks C and C^2 , said roll being pivoted at the 95 apex of a rectangularly bent bell crank lever D. This lever is adapted to swing about a pin d^2 on the frame of the machine and shows a nose d^3 which projects beyond the periphery of the roll d^1 and is adapted to co-operate 10

with the lateral lug c^1 of the disk C. The free end d^4 of the bell crank lever D rests upon an insulating piece e^5 connecting two yielding contact bars E^1 E^2 , Figs. 7 and 8. 5 These contact bars tend to lift the end d^4 of the lever D so that the roll d^1 engages the notches c^7 and c^8 when the latter are opposite the roll and the lug c^1 is out of the path of the nose d^3 .

10 The contact bars E^1 E^2 are conductively connected to the exciting winding F of the motor. In the position of rest, Fig. 7, of the mechanism, these bars abut against contact pieces e^6 , e^7 to which the armature of the 15 motor is connected. In the working position they abut against contact pieces e^8 , e^9 the piece e^8 of which is connected through the starting resistance H to the positive pole of the main, while the piece e^9 is connected to the contact piece e^6 . The conductor connected to the piece e^7 leads to the negative pole of the 20 main.

The described mechanism works as follows:

25 In the position of rest of the mechanism, Fig. 1, the surface b^7 of the locking lever B abuts against the lug c^1 of the locking disk C while its lug b^1 is in touch with the lugs a^3 and c^6 of the disks a^2 and C^2 . The spring c^3 30 is under tension so that the lower end of the slot c^5 of the switch disk C^2 abuts against the pin c^4 of the disk C. The notches c^7 , c^8 are opposite the roll d^1 so that the latter is held engaging said notches due to the spring 35 action of the contact bars E^1 , E^2 . The latter thus touch the upper contact pieces e^6 , e^7 . The circuit closed in this way is indicated in Fig. 7 by full lines. The positive conductor of the main is interrupted at e^8 and the motor 40 is not supplied with current.

45 When the operation of the machine is initiated by depressing a special key or the like, the locking lever B will be displaced so as to take the position of Fig. 5. When this takes place the three lugs c^1 , c^6 , a^3 are released by the surface b^7 and the lug b^1 of the lever B. Upon releasing the lug c^6 the switch disk C^2 50 suddenly rotates under the action of the spring c^3 so far in the direction of the arrow that the upper end of the slot c^5 engages the pin c^4 and the roll d^1 is pressed out of the notch c^7 by the cam-like lifting surface of the notch c^8 . The end d^4 of the lever D so depresses the contact bars E^1 E^2 that they come 55 into contact with the contact pieces e^3 e^4 and establish a circuit as illustrated in Fig. 8. This current flows from the + pole through H, e^8 , E^2 , F, E^1 , e^4 , G to the - pole and the motor will start. As the disk a^2 is allowed to 60 partake in the rotation of the worm wheel a^1 , the coupling between the worm wheel and the shaft A is effected so that the shaft A and the disk C rotate also. Consequently the smooth portion of the periphery of the disk 65 C will come opposite the roll d^1 and the contact bars E^1 E^2 remain locked in their depressed position.

Towards the end of the operation of the machine the locking lever B is brought by the bar b^4 back into locking position where its lug b^1 firstly stops the lug c^6 of the switch disk C² whilst the spring c^3 is tensioned again. Then also the lug a^3 of the disk a^2 is stopped by the lug b^1 of the lever B whereby the uncoupling of the worm wheel a^1 , still continuing to rotate, from the shaft A is caused. 70 Shortly thereafter, due to the inertia of the shaft the lug c^1 of the disk C hits the surface b^7 of the locking lever B so that the operating shaft A is stopped after having completed one revolution precisely. In the meantime the notches c^7 , c^8 had come to lie again opposite the roll d^1 and the latter would have been able to successively engage the notch c^7 as the upper edge of this notch moves upwards. But, 75 in order to secure a quick reversing of the contact bars so that formation of sparks is obviated, the lock c^1 d^3 acts in a manner such as to cause the roll d^1 to engage the notches only when it is opposite them with its entire 80 diameter. Upon this engagement by the roll taking place shortly before the operation of the machine is completed, the contact bars E^1 E^2 abut against the upper contact pieces e^6 , e^7 whereby the switch position of rest shown 85 in Fig. 7, is restored. The motor is thus cut off from the main and slows down without load by its inertia, since it has already been uncoupled from the operating mechanism of the machine and this mechanism has been 90 locked. As will be seen from Fig. 7, the armature of the motor is connected in series with the exciting winding F and this in a sense inverse to that of the working connection, 95 Fig. 8. A current will therefore arise in the 100 armature owing to the counter-electromotive force converted into electromotive force acting as in a generator, which current flows in the same direction through the field winding F as in the working connection of Fig. 8. 105 Consequently this current provokes a powerful braking field in which the armature will quickly come to rest. As in braking the armature the current decreases down to zero 110 and in the state of rest of the motor no current at all flows through the parts in question, the connections illustrated in Fig. 7 may remain also for the position of rest of the 115 described mechanism.

Claims:

1. In a machine of the class described, a driven shaft, an electromotor, a clutch between said driven shaft and said electromotor, means for controlling said clutch, means for arresting said driven shaft in a limit position, an armature and an exciting winding in said electromotor, a switch, circuit connections between said switch and said armature and exciting winding whereby said switch is adapted to short-circuit the armature solely 120

through the exciting winding, and connections between said clutch-controlling and arresting means and said switch, whereby said switch short-circuits the armature solely through the exciting winding upon said driven shaft having attained its limit position.

2. In a machine of the class described, a driven shaft, an electromotor, a clutch between said driven shaft and the electromotor, means for throwing in said clutch, means for throwing out said clutch, means for arresting said driven shaft in a limit position, an electric switch, an armature and an exciting winding in said electromotor, circuit connections between said switch and the armature and exciting winding, whereby the switch in a first position is adapted to short-circuit the armature solely through the exciting winding and in a second position to connect the armature in series with the exciting winding and a main, and connections between said clutch controlling means and said switch whereby the latter is brought into its first position upon the actuation of said throwing-out means and into its second position through the actuation of said throwing-in means.

The foregoing specification signed at Cologne, Germany, this 4th day of March, 1924.

AUGUST BESSLER.
